UNITED STATES PATENT OFFICE.

THOMAS FRENCH, OF GUELPH, ONTARIO, CANADA.

APPARATUS FOR MAKING IRON OXIDES.

Application filed May 4, 1921. Serial No. 406,689.

To all whom it may concern:

Be it known that I, THOMAS FRENCH, of the city of Guelph, in the county of Wellington, Province of Ontario, Canada, a subject of the King of Great Britain, have invented certain new and useful Improvements in Apparatus for Making Iron Oxides, of which the following is a specification.

10 This invention relates to means for producing iron oxides by subjecting iron salts, such as the sulphate, to an oxidizing roast. With existing apparatus for this purpose the difficulty is to satisfactorily control the 15 temperature and the amount of air admitted to re-act with the charge, and, when iron oxides are to be used as pigments, perfect control is essential to enable the exact shade of color desired in the finished product to be 20 obtained. This is particularly the case when the lighter shades of color are to be produced.

My object therefore is to devise a furnace which will enable an operator to perfectly 25 control both temperature and air admission and in which the means provided for admitting air are also best adapted to enable the progress of the reaction to be easily watched by the operator.

30 I attain my object by means of the construction hereinafter described and illustrated in the accompanying drawings in which—

Fig. 1 is a front elevation of my improved 35 furnace;

Fig. 2 a longitudinal section;

Fig. 3 a transverse section on the line *b*—*b* in Fig. 2; and

40 Fig. 4 a horizontal section on the line *c*—*c* in Fig. 2.

In the drawings like numerals of reference indicate corresponding parts in the different figures.

The furnace is constructed as usual of 45 brickwork and will be provided with the usual refractory linings wherever necessary. At one side of the furnace is located the fire place 1 provided with the usual doors and separated from the chamber 2 of 50 the furnace by a fire bridge 3. The furnace chamber is comparatively lofty and is provided with an arched roof as shown. At the opposite side of the chamber to the fire place is located a flue 4 communicating with 55 the interior of the chamber intermediate the top and bottom of the chamber. This

flue communicates with a chimney 5. The top of the chimney is preferably provided with a hinged damper 6, which, when closed, serves to direct gases and products of combustion passing up the chimney through a pipe 7 to a suitable condenser (not shown) in which condensable products are recovered.

In the chimney 5 is located a sliding 65 damper 8 by means of which the furnace chamber may be entirely cut off from communication with the chimney and the pipe 7 when desired.

In the front of the furnace are located 70 the working doors 9, the arrangement and proportioning of which forms an important part of the construction. These doors, it will be noted, serve to close an opening, the lower end of which is about at the level of 75 the floor of the chamber 2, and which opening is only about half the height of the chamber 2. The doors are double and are hinged at 10 by their outer edges on the outer wall of the furnace. From this 80 arrangement it follows that if the doors are partly opened, triangular spaces are left at the top and bottom of the doors and a vertical rectangular space between their adjacent edges.

85 In the front of the furnace I also prefer to form one or more small openings closed by hinged doors 11. These openings may be used, as well as the principal opening, for working the material within the furnace 90 with suitable rakes or pokers.

Over the doorway in the front of the furnace is located an external gas collecting hood 12 formed of any suitable material, which hood includes a flue 13 through 95 which gases may be led away. The upper end of this flue is provided with a damper 14 by means of which it may be closed as desired, while from the flue leads a pipe 15 through which acid fumes may be led away 100 to a condenser such as hereinbefore referred to.

The mode of operation of the furnace is substantially as follows. When a previous charge has been finished and withdrawn 105 from the furnace, the temperature in the furnace chamber has become somewhat lowered. The doors 9 and 11 are then closed and the dampers 6 and 8 opened. The fire in the fire place is made up and urged as 110 much as may be necessary. The interior of the furnace soon attains a bright red heat.

and a charge of the iron compound, usually ferrous sulphate, is introduced and spread out on the bed of the furnace chamber. The doors 9 are either kept closed altogether 5 at this stage or they are only slightly opened. As soon as the charge becomes sufficiently heated to give off its acid gas, the damper 8 is partially or wholly closed, depending on the furnace temperature, and 10 the doors 9 are opened a few inches. The opening of the door leaves a triangular space at the top and bottom as already described and through the lower space a current of air will enter the furnace in such a 15 way that it forms an oxidizing layer of air to a depth of a few inches above the surface of the charge and extending over every part of the bed of the furnace. When the damper 8 is closed, all the smoke and the 20 acid fumes from the decomposing sulphate emerge from the small triangular opening at the top of the partially opened doors 9. Thus within the upper part of the furnace chamber there is held, owing to its height 25 a large quantity of highly heated smoke and products of combustion which assists in maintaining the heat of the charge so that a very steady heat is obtained, which is easily regulated by opening or closing the doors 9 30 more or less as may be necessary. The current of air entering through the openings left at the bottom of the doors 9 causes rapid oxidation of the charge, which would soon become white hot if the doors were not further adjusted to admit a further amount of 35 cold air and to allow a more rapid escape of the heated gases in the upper part of the chamber. When the decomposition and oxidation of the charge becomes largely completed, the temperature tends to become too 40 low for the proper finishing of the operation. In this case the doors 9 will require to be further closed to prevent the entrance of too much air and the escape of too great 45 a quantity of the products of combustion, while the damper 18 may require to be more or less opened in order to increase the draft of the fire.

The charge in the furnace is turned over 50 frequently in order to expose new surfaces to the air. As soon as oxidation is complete, the charge is withdrawn from the furnace through the doors 9 and 11. The products of combustion and acid gases 55 emerging at the top of the doors 9 are collected by the hood and carried to the condenser as already described, as are also any gases passing through the flue 4 to the chimney 5. If for any reason the condenser 60 should be out of action, the products of combustion pass through the top of the

chimney and the top of the flue 13 leading from the hood, the dampers 6 and 14 being in that case opened up.

The rectangular opening between the adjacent edges of the doors 9, when the latter are partly open, gives an operator a perfect view of the interior of the furnace so that the condition of the charge at any moment is readily observed. 65

It will be understood that while this furnace is particularly adapted for the production of iron oxides from salts of iron, it may be used for roasting and calcining other ores. 70

It will be understood that either solid, liquid or gaseous fuels may be used in the fire place according to circumstances. 75

What I claim as my invention is:—

1. A furnace of the type described provided with a chamber; a fire place at one side of the chamber; a fire bridge separating the chamber from the fire place; a flue leading from the side of the furnace chamber opposite the fire place and intermediate the top and bottom of the chamber; a damper 80 in said flue; an opening in the front wall of the furnace materially less in height than the chamber and having its lower side substantially at the level of the chamber floor; a pair of doors vertically hinged by their outer edges at opposite sides of said opening; said doors being adapted to meet and close said opening when required or to open and leave openings above and below as well as between their adjacent edges when more 85 or less opened; and an external gas collecting hood over the opening and its doors. 90
2. A furnace of the type described provided with a chamber; a fire place at one side of the chamber; a fire bridge separating the chamber from the fire place; a flue leading from the side of the furnace chamber opposite the fire place and intermediate the top and bottom of the chamber; a damper in 100 said flue; an opening in the front wall of the furnace materially less in height than the chamber and having its lower side substantially at the level of the chamber floor; a pair of doors vertically hinged by their outer edges at opposite sides 105 of said opening; said doors being adapted to meet and close said opening when required or to open and leave openings above and below as well as between their adjacent edges when more or less opened, and one or 110 more small door-closed openings in the furnace wall adjacent the main opening; and an external gas collecting hood over the 115 openings and doors. 110

Signed at Toronto, Can., this 29th day of April, 1921.

THOMAS FRENCH.
